UNITED STATES PATENT OFFICE.

JOHN C. SCHAFFER, OF TOLEDO, OHIO.

KILN.

1,147,446.

Specification of Letters Patent. Patented July 20, 1915.

Application filed April 29, 1912. Serial No. 693,781.

To all whom it may concern:

Be it known that I, JOHN C. SCHAFFER, a citizen of the United States, residing at Toledo, Lucas county, Ohio, have invented new and useful Kilns, of which the following is a specification.

This invention relates to heating, heating duct connections, and kiln structures.

This invention has utility when embodied in kilns for firing or burning ware.

Referring to the drawings, Figure 1 is a plan view of an embodiment of the invention in connection with a group of kilns; Fig. 2 is a plan view, with parts broken away of one of the kilns; Fig. 3 is a fragmentary section through the kilns in line with the grouping; and Fig. 4 is a transverse section through one of the kilns.

The kilns 1 are provided with a plurality of furnaces 2 having grates 3 inclining downwardly toward the kiln. The hot gases from these furnaces pass upward in passage 4 within and around the outer sides of the kilns 1 toward the top of the kilns.

Referring to Fig. 1, closure 5, stops the top of kiln 6, so that the rising hot gases must pass down through the ware in this kiln charged with brick or other ware for firing or burning. These hot gases escape this kiln through the central opening 7 in the bottom thereof which has a central platform 8 therein directly covering the opening 9 to the subway duct 10, which has valve 11 opened to permit these hot waste gases from firing of kiln 6 to pass to kiln 12 for a pre-heating of the ware charged therein. As these heating gases come from duct 10 through opening 9, the platform 8 acts as a flare or distributor to deflect the heating

40 gases to thoroughly permeate the stacked ware as it passes into the kiln 12 through the central bottom opening 7. This heat utilization gives the kiln a preheating to a maximum temperature at the points most difficult to reach in the direct heating. Thus the updraft preheating, not only warms the entire kiln charge, but gives a distribution and partial firing to a greater or less extent, so that direct downdraft firing is most economically possible with enhanced uniformity of operation. The kilns are reversible in that in regular operation they may be first operated as updraft and then as downdraft kilns. The gases rising through the kiln 12

55 may pass out the opening 13 in the top there-

of, and through the removable elbow 14 placed in connecting position into utilization duct 15, which may lead by passage 16 to a drier or seasoner, or they may be used for such other purpose as may be desirable 50 in a ware manufacturing plant. Using this heat incidental to the manufacture, instead of for other purposes, or wasting entirely, contributes materially to the plant efficiency.

Were it found desirable, for reasons of 65 kiln repair, or charge not ready in kiln 12, the opening 7 might be blocked and duct 10 have its valve 11 removed to permit the gases to pass to and heat the next kiln 17, from which they might pass by elbow 14 into the 70 waste duct 18 having valves 19, 20, therein, to lead by the passage 21 to the stack 22. Accordingly there are two heat utilization ducts 15, 10, the former permitting conducting the hot gases elsewhere, while the latter 75 serve to conduct from kiln to kiln, or by passage 23 lead to the stack 22. The valves 19, 20 and 24 in the waste duct 18, permit operation of the circuit from the kilns in such direction to the stack as may be found 80 desirable. By the grouping of the kilns as shown, there may be extension in pairs for such enlarged capacity as may be desired from the initial installation.

Closures 25 may cover openings in the 85 duct 15 adjacent each kiln. To shut off communication of a kiln with the lower duct 10, closures 26 may be disposed to cover the openings 7. The elbows 14 are removable, insertible into the openings at the top of the 90 kilns, and reversible to enter either duct 15 or 18, there are accordingly provided two possibilities for carrying off the updraft gases. With closure 25 for the openings in ducts 15, 18, and closure 5 for the kiln opening 13, removal of closure 26 for the opening 7 about the flare hood or platform 8, permits of down draft operation controlled as to selecting of kilns by the valves 11 in the 95 duct 10.

In actual practice the gases from kiln 12 would not be of sufficiently high temperature for complete drying, and in most instances would be connected to duct 18 at this preheating. The greater advantage in the 105 use of the duct 15 is in carrying off the warm gases from a kiln after it has been fired and during the cooling operations. In regular rotation of the kilns of the plant, kiln 27 is shown as connected to duct 15 as it is cool- 110

ing. In the up draft operation a minimum of pressure is necessary as this is the natural course for the gases to take.

In operation, the kiln 6, Fig. 1, may be fired by its furnaces 2, the hot gases rising therefrom, acting downdraft, as the outlet means has closure 5 in position. These downdraft gases pass through the bottom opening 9, Fig. 4, to the duct 10 in which the control means 11 may be removed to give direct communication through the bottom opening 9 for updraft travel of these hot gases in kiln 12. The outlet means on kiln 12 may be disposed to communicate as desired. The elbow 14, in Fig. 1, has this kiln 12 in communication with the utilization duct 16, which may extend to a drier, or for such use as desired, while as readily it may be connected to the duct 18 to be acted upon by the draft inducing means or stack 22. This action is desirable in the earlier stages of the water smoking or drying out of the green ware in kiln 12, before the ware is to be subjected to firing, as the ware in kiln 6 is being treated. During this preheating and drying out of the ware in kiln 12 and the bringing up of the temperature therein for firing, the next kiln 17, may be charged, so that when kiln 12 is fired, it may have its hot gases act downdraft, instead of updraft as in the drying or preheating and these hot gases from kiln 12 pass for updraft warming of kiln 17. During this warming of kiln 17, the next kiln in series may be charged. As the furnaces on kiln 6 have firing thereof cease with the ware fully burned, there is considerable residual temperature in kiln 6 to be released through the top opening by removing the closure 5. The hotter portions of these cooling gases in passing the outlet means may be utilized by passing or being drawn through the utilization duct 15, while for hastening the later stages of cooling, there may be removal of the elbow, or connection to the duct 18. When the kiln 6 is sufficiently cooled to permit removal of the ware, such may occur, and the kiln be re-charged.

re-charged. In a series of kilns, by such successive handling, there is continuous firing possible, with economical use of the primarily heated gases, without detracting from the firing value thereof. The firing kiln acts right and on downdraft, and has the advantage of entry upon ware which has been well dried

from opposite heat travel, insuring good distribution throughout the kiln of properly burned ware. Upon firing, effective burning soon takes place, while the residual heat may be used in preliminary drying if desired. 60

What is claimed and it is desired to secure by Letters Patent is:

ure by Letters Patent is:
1. A series of kilns having connections for consecutive heating, firing and cooling, comprising firing means and bottom openings for the kilns, a duct directly connecting the bottom openings only of adjacent kilns for receiving down-draft firing gases from a first kiln and delivering for up-draft heating of a second kiln, draft inducing discharge means for the up-draft gases from the second kiln, and outlet means independent of said duct for conducting the gases from the first kiln after the firing thereof. 70 75

2. The combination with a first kiln, firing means therefor having its gases directed for down-draft operation, a second kiln, a duct from the first kiln to convey the gases from the down-draft firing of the first kiln for up-draft heating of the second kiln, a third kiln for charging, a fourth kiln, said kilns having central bottom openings, outlet means for updraft conveying spent heat gases from the fourth kiln, outlet means for the gases from the first kiln during the cooling thereof, control means for cutting off the duct connection between the first kiln and the second kiln after the firing of the first kiln, firing means for the second kiln having its gases directed for down-draft operation, a duct from the second kiln to convey gases from the down-draft firing of the second kiln for up-draft heating of the third kiln during the cooling of the first kiln, said down-draft receiving ducts being in communication with said up-draft receiving or cooling ducts only through the kilns, and said down-draft receiving ducts extending in a straight line between the bottom openings of adjacent kilns, said cooling of the first kiln occurring during the charging of the fourth kiln whereby in a series of kilns there may be continuous operation. 100

In testimony whereof I affix my signature 105
in the presence of two witnesses.
